SOUND REPRODUCING SYSTEM

John Hays Hammond, Jr., Gloucester, Mass.

Application January 22, 1931, Serial No. 510,382
Renewed September 22, 1933

13 Claims. (Cl. 179—100.4)

This invention relates to sound reproducing systems, and more particularly to an improved system for automatically expanding or multiplying the dynamic range of the sound energy.

5 The invention relates particularly to a system of amplification in which a greater ratio of amplification or gain is produced for impressed signals of high intensity than for impressed signals of low intensity, whereby the volume range of the 10 signal is expanded.

One of the purposes of this invention is to provide a method by which the scratch and ground noises ordinarily produced in the recording and reproduction of music or speech may be greatly 15 reduced or eliminated. Another purpose is to simplify the adjustment for a given expansion range and to simplify the construction of the device. This is accomplished by the use of an amplifying system comprising a number of stages in 20 cascade, the gain ratio of a plurality of said stages being controlled by the output of a single control device in accordance with the input signal strength of a stage subsequent to the first controlled stage, with the control so exercised that 25 the gain ratios of all controlled stages increase upon increase of signal input of the first controlled stage.

The invention also consists in certain new and original features of construction and combinations 30 of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which:

40 Fig. 1 illustrates diagrammatically the system as applied to the reproduction of the sound record of a talking moving picture projector, or of a phonograph; and

Figs. 2 and 3 are curves illustrating the operation of the system.

In the following description and in the claims, parts will be identified by specific names for convenience, but they are intended to be as generic in their application to similar parts as the art 50 will permit.

Referring more particularly to Fig. 1 a standard phonograph mechanism 10 is provided with the usual turntable 11 upon which rests a record 12. Engaging the sound groove of this record is the 55 needle of a phonograph pick up device 13, the

electrical output terminals of which are connected to two terminals of a double pole double throw switch 14. The other terminals of switch 14 are connected to the secondary of a transformer 15, the primary of which is connected through a battery 16 to a photoelectric cell 17. This cell is mounted behind a moving picture film 18, in front of which is an aperture plate 19 provided with an aperture 21 through which the light of a lamp 22 is focused by means of a lens 23. The blades of the switch 14 are connected to a potentiometer 24, which is connected across the primary of a transformer 25 the secondary of which is connected in the input circuit of a space discharge amplifier 26. The output circuit of this amplifier 15 is connected through a second transformer 27 to the input circuit of a second space discharge amplifier 28. A resistance 29 is connected in parallel with the primary of the transformer 27, in order to maintain the frequency characteristics 20 independent of the amplitude characteristics. 10

The secondary of transformer 27 is also connected through a stopping condenser 31 across a potentiometer 32, a variable section of which is connected through a leakage resistance 33 to 25 the input circuit of a control device 34.

The filaments of the devices 26, 28 and 34 are connected to one secondary winding of a transformer 35, the primary of which is connected to two conductors 36 and 37 which are connected 30 through a switch 38 to a source of alternating current supply 39. The anode of the device 34 is connected through the primary of a transformer 41 to a point 42 on a voltage dividing resistor assembly 43. One end 44 of this assembly is connected through the primaries of transformers 27 and 62 to the anodes of devices 26 and 28. The other end 50 of the resistor 43 is connected to one side of a resistance 55, which is connected in series with the secondary of transformers 41 and rectifier 59. Said resistance 55 is also connected in the control circuit of amplifiers 26 and 28 through the secondaries of the two transformers 25 and 27. The resistance 55 is shunted by a condenser bank 56 which is made 45 up of a plurality of condensers which, for example may vary from .5 to 4 microfarads. This condenser bank is controlled by means of a switch 57. One contact 58 of this switch is connected to a point 49 of the resistor assembly 43. The filament of rectifier 59 is energized by one of the secondaries of the transformers 35, and the heated cathode is connected to the mid-point of this secondary. The heated cathodes of the devices 26 and 28 are connected through an ammeter 61 55

50

to a point 46 of the resistance 43. The cathode of the device 34 is also connected directly to this point 46.

The output circuit of the amplifier 28 includes the primary of a transformer 62 which is shunted by a resistance 63, similar to resistance 29 above mentioned. The secondary of this transformer is connected to the input circuit of two space discharge amplifiers 64 and 65 which are connected 10 in push-pull. Connected across the secondary of transformer 62 is a condenser bank 66 consisting of a plurality of condensers which, for example may vary from .00025 to .00125 microfarads. This condenser bank is controlled by means of a 15 switch 67. The output circuits of the amplifiers 64 and 65 are connected to the primary of a transformer 68. The filaments of these devices are heated by a secondary winding 69a of a power supply transformer 69, the primary of 20 which is connected to the conductors 36 and 37. Across the filament circuit of the devices 64 and 65 is a resistance 74, the midpoint of which is connected to one end 44 of the resistor assembly 43. Rectifiers 72 and 73 have their cathodes 25 heated by secondary 69b and their space current supplied by secondary 69c of transformer 69. The positive lead of the rectifiers is connected through two choke coils 74 and 75 and the primary of the transformer 68 to the anodes of amplifiers 64 and 30 65. The negative lead is connected to point 50 of resistor 43. Connected across the output of the rectifiers 72 and 73 are three condensers 76, 77 and 78 which, together with the two choke coils 74 and 75 form a power filter of well known 35 form. Suitable by-pass condensers 45, 52 and 53 may also be connected across various sections of resistor 43.

The secondary of the transformer 68 is connected to the moving coil of a loud speaker 81, 40 the field of which is energized by a rectifier 82 which is supplied from the secondary of a transformer 83, the primary of which is connected to the conductors 36 and 37.

In the operation of the form of the invention 45 shown in Fig. 1, when it is desired to play the phonograph the switch 14 is thrown down, and when it is desired to use the moving picture apparatus the switch 14 is thrown up. The switch 38 is then closed which starts the phonograph mechanism 10, thus rotating the turntable 11 and record 12 in the usual manner. At the same time, the filaments of the devices 26, 28, 34, and 50 59 are heated by means of the energy passing thru the transformer 35. The filaments of the 55 devices 72 and 73 are heated by energy passing through part of the transformer 69, and the field winding of the loud speaker 81 is energized by energy passing through the transformer 83 and rectifier 82 which rectifies the current, causing a 60 direct current to flow through the field winding.

The rectifiers 72, 73, supply current to the anodes of amplifiers 64, 65, and to the resistor assembly 43, which is connected in series with the space current path of said amplifiers.

65 The resistor assembly supplies plate voltage for the devices 26 and 28 from point 44, and plate voltage for the device 34 from point 42. Biasing voltage for amplifiers 26 and 28 is supplied from point 50 through resistance 55. The amount 70 of bias is adjustable by resistance contact 47, which may be connected to point 50, to prevent loss of energy in that part of the resistance between 47 and 50. This is possible by the substantially constant current which flows through 75 the bias resistor assembly.

With no applied signal, the voltage on the grids of the devices 26 and 28 is determined by the setting of the movable contact 47 on resistor 43, which is so positioned that a small plate current will flow through these devices as indicated by the reading of the meter 61. When a signal is received from either the phonograph pick up 13 or the photoelectric cell 17, energy will pass through the transformer 25 to the input circuit of the device 26 where it will be amplified and 10 passed through the transformer 27 to the input circuit of the device 28. Part of this amplified energy will pass through the potentiometer 32 and leakage resistance 33 to the input circuit of the device 34. The output of this device passes through the transformer 41 and is rectified by the device 59 which is preferably a substantially linear rectifier. This rectified current passes through the resistance 55 in the direction of the arrow, thus causing a potential difference to be built up across this resistance which is proportional to the current flowing through it and, because of the linear nature of rectifier 59, substantially proportional to the input signal strength to control device 34. This potential difference will oppose the biasing voltage of the devices 26 and 28 as determined by the setting of the contact 47, thus decreasing the bias on these devices, which in turn decreases their impedance and, therefore, increases the amplification 20 of the stage in which they are connected. 25

It is thus seen that as the input signal strength increases, the amplification factor of the stages including devices 26 and 28 will be increased. In this way, the amplification factor is made small 35 for weak signals and large for strong signals. The output of the device 28 passes through the transformer 62 to the input circuit of the push-pull amplifier, comprising the devices 64 and 65 where it is amplified and fed through the transformer 68 to the moving coil of the loud speaker 81 where it is reproduced as speech or music in the usual way.

The potentiometer 24 controls the input signal strength and, therefore controls the total volume 45 of the system. The potentiometer 32 controls the signal strength applied to the grid of the device 34 with respect to the signal strength applied to the grid of the device 28, and in this way controls the dynamic range of the system, so that 50 when the potentiometer 32 is set to pick up a large amount of energy the dynamic range of the system will be large, and when the potentiometer is set to pick up a small amount of energy, the dynamic range will be small. It is to 55 be understood that potentiometers 24 and 32 may be operated simultaneously or independently as may be desired.

The leakage resistance 33 is placed in the input circuit of the device 34 so as to limit the output 60 of tube 34 and consequently of rectifier 59 and thus to prevent the bias on tubes 26 and 28 becoming so small as to cause tone distortion of the output of the system.

The condenser bank 56 is used to control the 65 time rate of decay or decrescendo. If the music is rapid and a quick response at the termination of the signal is desired, a small condenser is connected across the resistance 55 thus causing a rapid recovery; while if the music is slow, as in 70 organ recitals, a large condenser is used which causes a long decrescendo.

If it is desired to eliminate the dynamic multiplication entirely, the switch 57 is thrown on the contact 58 thus applying a suitable negative volt- 75

age from point 48 directly to the grid return connection of the devices 26 and 28 which then operate as normal amplifiers.

The condenser bank 66 is used as a tone filter 5 and provides a further control for the scratch attenuation.

In this invention it is necessary to shunt the primaries of both the transformers 27 and 62 by resistances 29 and 63 so as to maintain the 10 frequency characteristics of the amplifier stages independent of their gain ratio characteristics.

Fig. 2 is a curve depicting the decibels attenuation with different output volumes as measured by the plate current in meter 61. For example, 15 an output volume from loudspeaker 81 corresponding to a plate current of five milliamperes in meter 61 may represent a three decibel loss from the normal or optimum output due, for example, to filter 67. Minimum output volume 20 corresponding to a plate current of one milliampere may represent a loss of thirteen decibels from normal or optimum output. To obtain this relation, contact 47 may be adjusted to give a plate current of one milliampere with no signal. 25 As the grids of the amplifier tubes 26 and 28 swing more positive due to the signal causing a positive potential across biasing resistance 55, when approximately maximum or normal output 30 is reached, the attenuation will reach about three decibels loss. Thus from approximately normal or maximum output to approximately minimum or zero output, the scratch attenuation increases ten decibels.

Fig. 3 shows the relationship between the input 35 voltage to the amplifier and the bias on the grid of the amplifier. It is seen that this curve follows approximately a square law, so that when the input voltage is low a considerable increase therein will only produce a small decrease in bias, so that for weak signals the amplification factor is very low. With high input voltage a small increase therein produces a considerable decrease in bias, so that for strong signals, the amplification factor is very high.

The shape of this curve is due to the fact that 45 the input voltage for the control device is taken off subsequent to one of the controlled amplifiers (after amplifier tube 26), which causes the curve to follow approximately a square law.

Although only a few of the various forms in 50 which this invention may be embodied have been shown herein, it is to be understood that the invention is not limited to any specific construction, but might be embodied in various forms 55 without departing from the spirit of the invention or the scope of the appended claims.

What is claimed is:

1. A system for reproducing sound from a sound record comprising a plurality of stages of 60 amplification, each stage including a space discharge amplifier having a control element, an impedance in series with said control elements, said impedance being common to all of said stages, and means for passing a current through 65 said impedance, said current increasing with increase in strength of the input signal, said current being in a direction such that the potential drop in said impedance opposes the normal bias of said control elements, the relationship being 70 such that an increased signal strength decreases the normal negative bias of said control elements and causes an increase in the amplification ratio of the space discharge device.

2. A system for reproducing sound from a 75 sound record comprising a plurality of stages of

amplification, each stage including a space discharge amplifier having a control element, an impedance in series with said control elements, said impedance being common to all of said stages, means for passing a current through said 65 impedance proportional to the strength of the input signal and in a direction such that the potential drop in said impedance opposes the normal negative bias of said control elements, the relationship being such that an increased signal 10 strength decreases the normal negative bias of said control elements, and causes an increase in the amplification ratio of the space discharge devices, and a variable capacitance connected in parallel with said impedance and bearing such 15 relation thereto that the current passing through said impedance is proportional to the average value of the input signal over a predetermined period of time.

3. A method of operating a space discharge 20 amplifier for reproducing sound from a sound record comprising a plurality of stages of amplification which comprises causing the intensity of the input signal to vary the amplification factors of all of said stages in such manner that 25 an increased signal increases said amplification factors whereby the volume range of said amplifier is expanded.

4. A system for reproducing sound from a sound record comprising a plurality of amplifiers 30 arranged in cascade, a resistance common to all of said amplifiers and in series with their control elements, means for passing a current through said resistance which is dependent upon the input signal strength of one of said amplifiers whereby 35 the volume range of each stage of said amplifier is expanded.

5. A system for reproducing sound from a sound record comprising a plurality of stages of amplification each of said stages having a variable 40 amplification factor and a single means for controlling said amplification factor, said means being automatically operable in response to variations in signal strength, said control being adapted to cause the amplification factor to vary as an 45 increasing function of said signal strength whereby the volume range of the signal is expanded.

6. A system for reproducing sound from a sound record comprising a plurality of stages of amplification, a control means for controlling the 50 amplification factor of all of said stages, said means comprising an impedance carrying a current changing with the average value of the signal strength and a signal rectifier operated in accordance with the signal strength for controlling the current which is passed through said 55 impedance.

7. In a system for reproducing sound from a sound record including a plurality of space discharge amplifiers, a control circuit for said amplifiers operable in accordance with the average signal strength and adapted to control the gain ratio of said amplifiers, means for varying the timing of said control circuit, means for rendering said control circuit inoperative and a single 60 65 rotary switch for controlling both of said last mentioned means.

8. In a system for reproducing sound from a sound record including a plurality of space discharge amplifiers in cascade relationship, a control circuit for varying the amplification factor of said amplifiers and means for operating said control circuit in accordance with the signal strength at an intermediate point between the 70 controlled stages.

9. In a system for reproducing sound, a sound record, a pick-up device therefor, a multi-stage amplifier fed by said pick-up device, a translating device fed by said amplifier, a control circuit fed by the output of the first stage of said amplifier for controlling the gain ratios of both of said stages.
10. In a system for reproducing sound, a sound record, a pick-up device therefor, a multi-stage amplifier fed by said pick-up device, a translating device fed by said amplifier, and a control circuit fed by said pick-up device for controlling the gain ratios of both of said stages.
11. In a system for reproducing sound, a sound record, a pick-up device therefor, an amplifier fed by said pick-up device, a sound propagating receiver fed by said amplifier, a control circuit for controlling the gain ratio of said amplifier, means in said control circuit for rectifying the signal from said pick-up device and impressing the same across a biasing resistance and a variable capacitance across said biasing resistance to vary the timing of the dynamic action.
12. In a system for reproducing sound, a sound record, a pick-up device therefor, an amplifier fed by said pick-up device, a translating device fed by said amplifier, means for controlling the amplification ratio of said amplifier responsive to the volume output thereof, and means for adjusting the range of said controlling means.
13. In a system for reproducing sound from a sound record, a plurality of amplifying means having variable amplification ratios, and a single means to control the amplification ratios of all of said amplifying means, said control means being responsive to the average energy received from said sound record.

JOHN HAYS HAMMOND, JR.
